US00D770616S

(12) **United States Design Patent** (10) **Patent No.:** **US D770,616 S**
(45) **Date of Patent:** ** *Nov. 1, 2016

(54) **MEDICAL DEVICE HANDLE**(71) Applicant: **The Spectranetics Corporation**,
Colorado Springs, CO (US)3,614,953 A 10/1971 Moss
4,051,596 A 10/1977 Hofmann
4,203,444 A 5/1980 Bonnell et al.
4,246,902 A 1/1981 Martinez(72) Inventors: **Phillip Charles Halbert**, San
Francisco, CA (US); **Christopher Allen
Wilson**, Oakland, CA (US)

(Continued)

(73) Assignee: **The Spectranetics Corporation**,
Colorado Springs, CO (US)

Primary Examiner — Wan Laymon*Assistant Examiner* — Mark Booker(74) *Attorney, Agent, or Firm* — Faegre Baker Daniels
LLP(57) **CLAIM**The ornamental design for medical device handle, as shown
and described.**DESCRIPTION**FIG. 1 is a front perspective view of medical device handle
illustrating our new design;

FIG. 2 is a front side view thereof;

FIG. 3 is a back side view thereof;

FIG. 4 is a left side view thereof;

FIG. 5 is a right side view thereof;

FIG. 6 is a top view thereof; and,

FIG. 7 is a bottom view thereof.

The portions of the device shown in broken lines form no
part of the claimed design.**1 Claim, 5 Drawing Sheets**(56)
